GUIDING AND FEEDING MECHANISM FOR
ENDLESS TYPEWRITER RIBBONS

Augusto Leite Pessoa, Rio de Janeiro, Brazil

Application July 14, 1948, Serial No. 38,715
In Brazil August 18, 1947

3 Claims. (Cl. 197—168)

1

This invention relates to a new device for use in connection with typewriters and consists of two rectangular boxes of metal or plastic adaptable to any typewriting machine of modern construction the covering or upper body of which, in front of the platen, is unobstructed by any other part or device. The said boxes contain the suitably prepared typewriter ribbon and control it without the use of spools as now used; they simplify the placing and replacing of the ribbon and avoid, on the other hand, that the operator gets his fingers stained when placing it in the machine.

The two boxes forming the object of the present invention are each divided into two distinct bodies which are of different size, but cooperate with each other, the smaller serving as a slide for the larger. The smaller body "B" of each box is slidably mounted in the device by means of a system of rollers. The larger body "A" is fixedly secured to the frame of the typewriter. Internally, the two boxes are divided into cavities arranged so as to let the ribbon pass in a horizontal direction guided by two trailer posts each formed by a vertical pin around which turn rollers, the posts being disposed at the two extreme corners of each box. The ribbon being of the endless ribbon type has a length of 1 m. or a little more and a width of 13 mm., approximately. The said boxes are mounted on the machine so as to make use of the holes, already existing thereon, and serve as permanent containers for the ribbon. The application of the new device makes it necessary to remove the present receptacles for the ribbon which are situated on the upper part of the machine. At those points two sets of pressure rolls are mounted which serve the purpose of actuating the typewriter ribbon.

At present, whenever the typist wishes to replace the ribbon, he has to execute a number of operations, adjustments and the like as follows:

1. The ribbon must be wound completely on one of the spools, which is obtained by turning a suitable handle in one direction only;
2. Both spools must be removed from the receptacles where they are mounted on rotatory shafts;
3. The worn ribbon must be detached from the arrowheaded hook or clip provided in the middle of the spool on which the ribbon is wound up;
4. The new ribbon must be grasped by the fingers and threaded into the slot and attached to the hook or clip;

5. The spools must again be mounted on their respective shafts situated on top of the body of the machine;

6. The ribbon must also be threaded again through the ribbon-carrier in the center where the type prints, and inserted into the ribbon holders;

7. The crank handle must be turned for winding the ribbon, and other operations must also be executed.

At present, whenever the ribbon movement reaches its end on one of the spools, the automatic reverse mechanism causes the ribbon to move in the opposite direction. As, however, this reverse gets easily jammed, the operator has to be on the alert every time the ribbon reaches that point.

The present invention eliminates many of these drawbacks and has the following advantages over the customary method of winding the ribbon on the spools:

(a) Complete utilization of the ribbon which will serve until it is worn out or torn;

(b) A shorter ribbon which, therefore, will be cheaper; while the common ribbons have a length of 6 to 8 meters, the ribbon used in the present invention is only about one meter long;

(c) Easy and quick insertion of the ribbon into the permanent casing, without the need of skill or training;

(d) Clear print, as the operator can always make it come out stronger by adding or restoring the ink on the ribbon by means of a brush and special ink, which is done in no time;

(e) Durability of the ribbon compared to the ones at present in use, considering that it can be restored, as stated above, and that a stronger fabric can be used for the new ribbons;

(f) The soiling of one's fingers is avoided, because the ribbon is carried and extended on the back of the thumb and first finger and allowed to fall by itself into place between the two driving rolls and against the four trailer posts in the corners of the ribbon boxes;

(g) The use of spools is dispensed with;

(h) The jamming of the ribbon mechanism and the automatic reverse is avoided, inasmuch as the ribbon always runs in one direction, there being no need for it to run in different directions;

(i) No change is necessary in the machine or its structural parts. Only a small cut is required in the upper cover and laterally on both sides and furthermore, the substitution of the shaft of the spools by another exactly alike, but

not united with the spool container, as is now the case;

(j) The cost of a typewriter ribbon is considerably reduced;

(k) The typewriting machine is given a more beautiful and more stylish appearance.

The present invention is illustrated in the accompanying drawings in which:

Fig. 1 shows the whole novel device according to the invention mounted on a typewriting machine of modern construction;

Fig. 2 shows, in detail, the two boxes of metal or other suitable material, with the two cover plates, removably situated on both sides and within which the ribbon is threaded around movable rollers or trailer posts at the four corners of the said boxes and through the two systems of cylinders or rolls, the ribbon being finally also threaded through the ribbon-carrier in the center where the type prints;

Fig. 3 shows a slide B to be slidably mounted on each one of the frames A, as indicated in the preceding figure;

Fig. 4 presents a device consisting of a button with a rod having two gears to be mounted on two racks whereby the tension of the ribbon used in the novel device is controlled;

Fig. 5 shows a system on which a pin or trailer post is flexibly mounted which maintains the ribbon in upright position, allowing for a certain flexibility;

Fig. 6 is a system of cylinders or pressure rolls serving as a ribbon drive when they are pressed against each other;

Fig. 7 shows an inked ribbon of the endless type, being about 1 meter long.

As will be seen from the drawing, the new device adaptable to typewriting machines for ribbon control and invented for this purpose, essentially consists of two rectangular boxes 1 (Figs. 1 and 2) each of which is internally divided into two distinct parts or compartments. The first part is formed by a plate A, having vertically mounted thereon four walls 2a, which form two open parallel channels within which runs the typewriter ribbon 6. A cover plate 3 is hinged to one wall so as to permit closing the ribbon casing completely in order to prevent dust and foreign matter from entering the casing. The arrangement, furthermore, comprises a pressure roll system 18, 19 which can be closed and opened by means of an arm 22 so as to allow of the ribbon 6 being threaded and guided around the trailer posts 5 and through the above-mentioned channels while holding the ribbon under proper tension. The second part of the said box slides within the first part, already described, by means of a roller system controlled by a knob 7. This second part comprises (Fig. 3) a plate B on which are mounted six walls 2b, arranged in the form of two U's with the legs of the U's in substantial alignment with the respective walls 2a. Through the channel thus formed the ribbon 6 moves supported by the trailer posts 5. This assembly is located in the lower outer part of the slide B. Two rack rails 10 are secured to the plate A which rails cooperate with the rollers or pinions 9 so as to permit that the two parts of each one of the said boxes become sufficiently narrowed or spaced to facilitate inserting the ribbon into the casing and keeping it conveniently stretched (Fig. 4). The rollers or pinions 9 are operable by means of a shaft 8a ending in a knob 7. A fitting 11 is mounted on plate B and in this fitting slides a disc 13 having a spring 14 fastened at the point 15, this disc

having secured thereto a post 5 enclosed in a movable roller 12. This arrangement serves the purpose of giving the ribbon a certain flexibility, especially when the keys are shifted to write capital letters or upper case characters, that is, the ribbon-carrier reaches its highest position (Fig. 5). The system furthermore includes two L-shaped metal pieces 16 and 17, and a spring 23 positioned so that the parts supporting the pressure rolls 18 and 19 are brought together or separated by means of the control lever 22. The reference 20 indicates the spool shaft of the typewriter itself on which at present the spool with the ribbon is mounted and which is now made use of to transmit rotatory movement to the pressure rolls 18 and 19. The roll 19 is mounted at 21, while the ribbon passes between the said pressure rolls which exert a pull on it so that it moves within its casing. The typewriter ribbon consists of an endless ribbon 6 (Fig. 9), made of stronger fabric than those now in use, and the ink on which can always be restored when it is desired to obtain a fresher print on the paper without the necessity of removing the ribbon from its casing.

The device according to the invention may be installed as follows: First, the carriage of the typewriter is moved so as to position the platen in the center. Then the cover is lifted off the machine or the top of the body, as may be the case, to permit removal of the spools and the respective ribbon holders or spool guards located inside. The two metal boxes of the present invention are then screwed on to the apertures existing on the machine and are thus secured externally to the machine like two wings, as shown in Fig. 1. By turning the knobs 7, the two plates A of the boxes are adjusted relative to each other so as to facilitate placing the suitably prepared typewriter ribbon inside. After first lifting off the covers or lids of the novel arrangement, the ribbon is gripped by the tips of the thumb and first finger so that it rests against the backs of the same, whereupon the ribbon is dropped into its proper position, that is, between the pressure rolls (Fig. 6), previously opened by means of their control levers 22, and is passed around the trailer posts 5 (Figures 2 and 3), situated in each corner of the rectangular boxes. Now the ribbon is threaded through the ribbon-carrier, and each one of the knobs 7 is actuated suitably to stretch the ribbon inside its casing. After the closing system of one of the pressure rolls has been actuated the top covers of the machine and of the novel device are closed. Thus, when operating the machine in the usual manner, the shaft 20 will rotate, driving in its turn the ribbon inside the casing and consequently threading it through the ribbon-carrier of the typewriter.

All these operations are extremely easy, and are effected in very much less time than is required at present for placing or replacing a typewriter ribbon. A further advantage consists in a considerable reduction in the cost of the ribbon which may be re-inked at any time. To this end, the ribbon is moved by means of a crank lever provided in the machine, and ink is applied to each side of the ribbon throughout its length by means of a brush. If at the end of a day's work it is noted that the print becomes faint or not clearly legible, it will be enough to restore the ink as just mentioned and, next day, typing can be resumed without risk of blotting or blurring or any other inconvenience. For this purpose a quick-drying ink

will be used. Such restoration will only be made in the case mentioned and not daily.

It will be understood that the present invention may undergo many different modifications in its component or structural parts without departing from its principle and scope as set forth in the following claims.

I claim:

1. A device for typewriters which eliminates the use of the usual spools and ribbon holders and conveyors, comprising two rectangular outer housings having a base and three side portions, said housings being adapted to be disposed on the cover plate of a typewriting machine, said base of each outer housing having slots, an inner housing similar to each of the outer housings but of smaller dimensions lodged inside each of said outer housings so that all side portions are parallel to the three side portions of the outer housings and located at a short distance from these side portions, thus forming a continuous and relatively narrow passage for the typewriter ribbon, trailer posts projecting vertically from and guided in said slots, additional posts located on the base of said outer housings adjacent their open sides and aligned with certain of the vertical posts, and a relatively large pressure disc adjacent each one of the said additional posts, whereby a typewriter ribbon may be positioned in the continuous and narrow passage formed between the side portions of the outer and inner housings and passed around the vertical posts, between the additional posts and discs at the open sides of the outer housings, and through the usual ribbon carrier.

2. In a guiding and feeding mechanism for endless typewriter ribbons, two spaced housings adapted to be arranged on the cover plate of a typewriter, each of said housings comprising a substantially U-shaped outer vertical wall, and a correspondingly shaped inner vertical wall spaced from said outer wall so as to form therewith a passage for a typewriter ribbon, each of said housings being transversely divided to form

two relatively adjustable parts, rack means connected to one of said parts, pinion means carried by the adjacent other part and arranged for engagement with said rack means to thereby effect relative adjustment of the respective housing, manually operable means operatively connected with said pinion means for actuating the same, yieldably mounted trailer posts within said housings for guiding a typewriter ribbon in said housings, frictional driving means within said housings for frictionally engaging and driving said ribbon, and means operatively connected with said frictional driving means and manually operable for selectively disengaging said ribbon.

3. Guide and feeding mechanism for typewriter ribbons comprising in combination, a pair of spaced first supporting means respectively arranged at both sides of a typewriter, second supporting means respectively associated with said first supporting means and movable relative thereto, two pairs of spaced guide posts, each pair being associated with one of said second supporting means and being yieldably supported, two pairs of tension rollers respectively associated with said first supporting means, means connected to at least one of said rollers for rotating the same in response to the actuation of the keys of said typewriter, and means operatively connected with each first supporting means and the adjacent second supporting means for effecting relative movement therebetween.
